Attorney

UNITED STATES PATENT OFFICE.

ELIAS CALVIN HOLLAND, OF AUSTIN, ASSIGNOR TO THE UNION SPECIAL SEWING MACHINE COMPANY, OF CHICAGO, ILLINOIS.

END-CAP FOR CYLINDER SEWING-MACHINES.

SPECIFICATION forming part of Letters Patent No. 519,909, dated May 15, 1894.

Application filed July 11, 1893. Serial No. 480,148. (No model.)

To all whom it may concern:

Be it known that I, ELIAS CALVIN HOLLAND, a citizen of the United States, residing at Austin, in the county of Cook and State of Illinois, have invented certain new and useful Improvements in End-Caps for Cylinder Sewing-Machines, of which the following is a description, reference being had to the accompanying drawings, and to the letters of reference marked thereon.

My invention relates to an improvement in sewing machines and particularly to those having a cylindrical bed plate, and my object is to provide a new form of end cap for use on such machines.

The invention consists in the various details of construction of the parts all as hereinafter described and claimed.

The invention is illustrated in the accompanying drawings, in which—

Figure 1 is a side elevation partly in section, showing my invention as applied in full lines for closing the cylinder and in dotted lines as swung back to enable the operator to gain access to the interior of the cylinder. Fig. 2 is a bottom plan view, and Fig. 3 is an end view of my invention.

In the drawings A represents the cylinder or bed plate of the sewing machine to which my invention is to be applied, and B represents the end cap for closing the same. The cap B is made approximately bell-shaped, and the apex is cut off as shown. The underside of the cap is flattened as shown at a and is provided with a downwardly projecting lug b.

Secured to the end of the casing by means of screws passing through holes c is a segment C, the outer periphery of which preferably follows the curve of the rim d of the cap B. This segment C has outwardly projecting lugs e which are sufficiently separated to permit the insertion of the lug b between them, said lug being pivoted to them by means of the pin f passing through all three.

A curved plate spring D is secured by means of the screw g to the flattened face of the cap B, and is curved outwardly at its inner end

so as to bear on the lugs e, thereby holding the cap whether in its opened or closed position. Suitable notches are formed on the upper side of the cap to enable the operator to more readily open the cap when desired. The rim of the cap B and the inner face of the segment C is provided with suitable recesses to accommodate the ends of the various shafts located within the cylinder.

As heretofore constructed, the end cap has been extended out to a point, and with such a construction certain sizes of shoes would not fit upon the cylinder, hence the reason for shaping my end cap as shown.

Having thus described my invention, what I claim, and desire to secure by Letters Patent, is—

1. In combination with a sewing machine having a cylindrical casing forming the bed plate, a device for closing the end of said casing comprising a tapering end cap having a rim fitting against the end of the bed plate of the machine, said cap having a flattened under side, a lug secured thereto, a rigid segment secured to the casing and to which the lug is pivoted, and a spring for holding the cap in its opened or closed position; substantially as described.

2. In combination with a sewing machine having a cylindrical casing forming the bed plate, a device for closing the end of said casing comprising a tapering end cap having a rim fitting against the end of the bed plate of the machine, said cap having a flattened under side and provided with a lug b, a segment C secured to the casing, and having lugs e, a pivot pin passing through the lugs b and e, and a spring D secured to the cap B and having a downwardly curved end bearing on the lugs e, said cap having an opening at its outer end; substantially as described.

In testimony whereof I affix my signature in presence of two witnesses.

ELIAS CALVIN HOLLAND.
